UNITED STATES PATENT OFFICE.

JAMES G. McNAMARA, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed March 15, 1926. Serial No. 94,657.

This invention relates to typographical distributing machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In some machines, such as the commercial Model 9, where matrices may be drawn from several magazines and mixed together in the same line, the distributing mechanism includes a primary distributor which first sorts the matrices according to font, and a plurality of main distributors which thereafter sort the matrices of the individual fonts according to character and restore them to their proper channels in the magazines. With this type of distributing mechanism, the matrices, after font separation, pass down chutes or tubes and enter so-called lower distributor boxes, wherein they are guided upon inclined rails into engagement with reciprocating pawls or escapements, which feed them one at a time to the main distributor. In order that these pawls or escapements may cooperate properly with the matrices, the latter are provided in their bottom edges with central notches, which necessarily vary in shape and depth according to the thickness of the individual matrices. Besides adding to the cost of production, such notches in the matrices materially limit the space ordinarily required for the regular font notches and, moreover seriously weaken the matrices, especially when the latter are formed with other necessary cuts or notches. Furthermore, matrices comprising fonts used on other machines, such as those of the single distributor class, are excluded from use on machines of the multiple distributor class described, since they do not have the required central notches.

The present invention is intended to obviate the foregoing difficulties and contemplates certain improvements whereby the distributing mechanism may receive and handle matrices of all fonts whether they

have or have not the objectionable central notches referred to. To this end, each of the lower distributor boxes is provided with an escapement device arranged to cooperate with the upper ends of the matrices and which device not only serves its primary purpose of feeding the matrices one by one to the distributor screws but also to accelerate the delivery of the individual matrices to the screws. In the embodiment illustrated, there are employed two cooperating escapement members movable together as one at one stage and relatively to each other at another stage in controlling the passage of the gravitating matrices one at a time to the screws, one of said members being in the form of a pivoted finger which permits final escape of the matrices, and the other being in the form of a reciprocating slide which aids in effecting their separation and which hastens their delivery to the screws.

In the accompanying drawings, the invention has been shown merely in preferred form and by way of example and as applied to the specific type of distributing mechanism indicated. However, many changes and variations may be made therein and in its mode of application, which will still be comprised within its spirit. It is to be understood, therefore, that the invention is not limited to any specific form or embodiment except in so far as such limitations are specified in the claims.

Referring to the drawings:

Fig. 1 is a rear elevation of a lower distributor box partly broken away and equipped with the present improvements;

Fig. 2 is an end view of the box removed;

Fig. 3 is a detailed horizontal section, taken on line 3-3 of Fig. 1;

Figs. 4 and 5 are fragmentary side views, showing the escapement device in different positions during the release of a matrix; and

Fig. 6 is a detail perspective view of the escapement device proper.

The matrices X are released by the primary distributor (not shown) into the tubes G and enter one or another of the lower distributor boxes A, wherein they are guided and sustained by their projecting ears x upon upper and lower inclined rails A¹ A², which direct them to the receiving end of the associated main distributor. The latter comprises the usual longitudinally ribbed

bar B and the set of constantly driven matrix conveying screws B¹ which are arranged to pick up the matrices as they escape from the box and advance them across the horizontal rail extensions A³ into engagement with the bar B and thence along the same until finally released above their respective magazine channels. The foregoing parts and their mode of operation except as hereininafter pointed out are or may be of any approved construction or as embodied in the commercial Model 9 linotype.

As shown in Fig. 1, matrices passing from the chute G are straightened up within the box A at XI in the usual way so as to properly engage the upper and lower guide rails A¹ A², down which they slide by gravity in upright position until arrested adjacent the receiving ends of the screws B by the escapement device forming the subject matter of the present invention. This device is arranged to cooperate with the upper ends of the matrices and acts to control their passage one at a time into position to be picked up by the distributor screws, irrespective of the presence or absence of the central notches hereinbefore mentioned. In the embodiment illustrated, the improved escapement device comprises a vertical reciprocating slide C and an oscillatory finger C¹, the latter being pivotally mounted at its upper end to the slide C and provided with a crank arm C², which is connected to the operating means later to be described. At its lower end, the finger C¹ is formed with a lip C⁶ projecting beneath the slide C and arranged to intercept the matrices as they pass down the inclined rails A¹ A². A spring C⁷ connected to a pin C⁸ on the rear edge of the finger C¹, and of sufficient strength to withstand the impact of the gravitating matrices, controls the pivotal action of the finger and constitutes the medium through which the escapement device proper is moved downwardly by the crank arm C². The slide C is mounted in the front end of the box A and is slotted at C³ (Fig. 2) to receive a retaining screw C⁴ and a stud C⁵, which serve respectively to limit its strokes in opposite directions, the arrangement being such that on the down-stroke of the slide a matrix arrested by the lip C⁶ of the finger C¹ will be engaged by the slide and pushed thereby along the guide rails A¹ A² toward the pick-up position. This feature, while perhaps not absolutely essential, is particularly desirable since it insures the delivery of the matrices to the screws quicker and at more regular intervals than heretofore, irrespective of thickness, it being understood that in boxes of the type illustrated, where gravity alone is depended upon, the thinner matrices, being lighter and more liable to slight interferences than those of the thicker variety, are frequently delayed

and hence are more apt to cause clogging and stoppage of the distributor. It will be observed from Figs. 1 and 4, which show the device in raised positions, that the arresting surface C⁹ of the lip C⁶ is spaced from the rear face of the slide C at a distance slightly less than the thickness of the thinnest matrices so that only one matrix may be engaged by the slide C at a time. This relation, in the present instance, is maintained by a spacing stud C¹⁰ (shown best in Fig. 5) arranged between the two escapement members. In practice, however, it might be found desirable to make this stud C¹⁰ adjustable, instead of a fixed part of the finger C¹ (as indicated) and thereby facilitate the original setting of the device as well as compensate for the wear resulting from continued use.

Since it is essential to the proper distribution of matrices that they be fed to the distributor at a rate determined by the rate of rotation of the distributor screws, the escapement device is operated in the customary way from a cam B² secured to the end of one of the screw spindles B³, the desired motion being imparted to the device through a bell crank lever D pivoted at D¹ to the box A. The longer horizontal arm D² of this lever is loosely connected to the free end of the crank arm C², before mentioned, while the shorter arm D³ thereof (see Fig. 1) is provided with an anti-friction roller D⁴ arranged to engage the face of the cam B², against which it is constantly held by a pull spring D⁵ anchored to the distributor box A. According to this arrangement, as the cam B² is rotated, the bell crank lever D will be rocked and the escapement device operated in the required synchronism with the distributor screws, the upstroke being effected by the spring D⁵ and the down-stroke through the medium of the spring C⁷, as above stated. An element of safety is thus provided in the operation of the device, since, if positive connections were employed, a clogged matrix or other obstruction would probably cause breakage of the parts and damage to the matrices.

The operation will now be clear: As the lever D is rocked by the cam B² to move the escapement device downwardly, an arrested matrix (Fig. 1) will be engaged by the slide C (Fig. 4) and pushed thereby down the inclined rails A¹ until said slide is arrested by the stud C⁵. At this point of the operation (see Fig. 5), it will be noted that the finger C¹ has been rocked slightly forward against the tension of the spring C⁷ and that the slide C occupies a position low enough to arrest any following matrices that might have accumulated in the box. In order to obviate wear on the upper ears of the matrices, which might result if they were obliged to displace the finger C¹ dur-

ing their depression (as they could do), a cam plate A⁴ is fastened to the box A in position to be engaged by the pin C⁸ of the finger C¹ immediately the slide C comes in contact with the upper end of the arrested matrix (Fig. 4). In this way, the slight forward displacement of the finger C¹ from the position shown in Fig. 4 to the full line position shown in Fig. 5 is effected by the cam plate A⁴ instead of by the matrices themselves. In completing its stroke from the full line to the dotted line position, Fig. 5, the lever arm D² through the crank arm C² rocks the finger C out of the way of the depressed matrix so that it may escape or pass on to the pick-up position of the distributor screws. On the return movement of the lever arm D², the finger C¹ is rocked back to its original position as determined by the engagement of the stud C¹⁰ with the slide C, and the lip C⁶ thereby located in proper relation to the slide, which is then restored to its upper position to allow the next matrix (which now becomes the leading one) to slide beneath it into contact with the arresting face C⁹ of the lip C⁶.

It is pointed out that while the actual operation takes place in the manner just described, the movements of the parts are very rapid, the escapement device being actuated at each rotation of the distributor screws so as to feed the matrices thereto one at each cycle of operation. The reciprocations of the slide C and the oscillations of the finger C¹ are so timed that the former acts as an accelerator to each matrix as it is detached or separated from the others and thus insures the proper delivery of the matrices to the screws.

Having thus described my invention, its construction and mode of operation, what I claim and desire to secure by Letters Patent of the United States, is as follows:

1. In a typographical distributing mechanism comprising a distributor bar and set of matrix conveying screws, the combination of guide means along which the matrices gravitate toward the screws, and an escapement device arranged to cooperate with the upper ends of the matrices and acting solely to control their passage one at a time into position to be picked up by the screws.

2. In a typographical distributing mechanism comprising a distributor bar and a set of matrix conveying screws, the combination of guide means along which the matrices gravitate toward the screws, and an escapement device arranged to cooperate with the upper ends of the matrices and acting to control their passage one at a time into position to be picked up by the screws, said escapement device comprising two cooperating members movable together as one at one stage and movable relatively to each

other at another stage in effecting the release of the individual matrices.

3. In a typographical distributing mechanism comprising a distributor bar and a set of matrix conveying screws, the combination of guide means along which the matrices gravitate toward the screws, and an escapement device comprising a vertical reciprocating member and a cooperating oscillatory member, the said members being movable together as one at one stage and relatively to each other at another stage in effecting the release of the matrices one at a time into position to be picked up by the screws.

4. In a typographical distributing mechanism comprising a distributor bar and a set of matrix conveying screws, the combination of guide means along which the matrices gravitate toward the screws, and an escapement device arranged to cooperate with the upper ends of the matrices and comprising a vertical reciprocating member and a cooperating oscillatory member pivoted thereto, said members being movable together as one at one stage and relatively to each other at another stage in effecting the release of the matrices one at a time into position to be picked up by the screws.

5. In a typographical distributing mechanism comprising a distributor bar and a set of matrix conveying screws, the combination of guide means along which the matrices gravitate toward the screws, and an escapement device arranged to cooperate with the upper ends of the matrices and acting alternately to arrest and release the individual gravitating matrices and serving to accelerate the delivery of the detached matrices into position to be picked up by the screws.

6. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, the said device comprising a vertically reciprocating and oscillatory member operative when in its upper position to arrest the descending matrices and operative when in its lower position to release them.

7. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, and comprising a vertical reciprocating slide and an oscillatory finger pivoted thereto, the said finger in the upper position of the slide act-

- ing to arrest the leading matrix and in the lower position of the slide being swung clear of said matrix to permit it to escape, and the said slide when in its upper position standing clear of the descending matrices to permit the leading one to be arrested by the finger, but acting during its reciprocation to hold back the following matrices.
8. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, and comprising a vertical reciprocating slide and an oscillatory finger pivoted thereto, the said slide in its upper position standing clear of the descending matrices but acting during its reciprocation to depress the leading matrix and hold back the following matrices, and the said finger in the upper position of the slide acting to arrest the leading matrix in engaging relation thereto and in the lower position of the slide being swung clear of the depressed matrix to permit it to escape.
9. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, the said device comprising a vertical reciprocating slide and an oscillatory finger pivoted thereto, and common means for actuating the slide and finger.
10. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, the said device comprising a vertical reciprocating slide and an oscillatory finger pivoted thereto, means for imparting the reciprocating and oscillatory movements to the slide and finger, and a spring connected to the finger and tending constantly to hold it in its matrix-retaining condition.
11. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, the said device comprising a vertical reciprocating slide and an oscillatory finger pivoted thereto, a spring connected to the pivoted finger and tending constantly to hold it in its matrix-retaining condition, an arm also connected to said pivoted finger and adapted when operated to swing it outward to its matrix-releasing position, and an actuating lever connected to said finger arm and serving through the medium of said arm to impart the reciprocating and oscillatory movements to the slide and finger.
12. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, the said device comprising a vertical reciprocating slide and an oscillatory finger pivoted thereto, a spring connected to the pivoted finger and tending constantly to hold it in its matrix-retaining condition, an arm also connected to said pivoted finger and adapted when operated to swing it outward to its matrix-releasing position, and an actuating lever connected to said finger arm and serving through the medium of said arm to impart the reciprocating and oscillatory movements to the slide and finger, together with a cam arranged to engage the pivoted finger and swing it outward slightly during the downstroke of the slide.
13. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, the said device comprising a vertical reciprocating slide and an oscillatory finger pivoted thereto, and actuating means for the slide and finger acting to move them downward together as a unit and then at the completion of the downward stroke to swing the finger outwardly away from the slide.
14. In a typographical distributing mechanism comprising a distributor bar and a set of matrix conveying screws, the combination of guide means along which the matrices gravitate toward the screws, and an escapement device controlling the passage of the gravitating matrices one at a time into position to be picked up by the screws, the said device comprising the vertical slide C formed with the slot C³, the stop pins C⁴, C⁵ arranged within the slot C³, the finger C¹ pivoted to the slide C and provided with the arm C² and projecting pin C⁶, the spring C⁷ connected to the pin C⁶, and the operating lever D having its arm D² connected to the arm C², all substantially as shown and described.
15. In a typographical distributing mech-

anism comprising a distributor bar and a set of matrix conveying screws, the combination of guide means along which the matrices gravitate toward the screws, and an escapement device controlling the passage of the gravitating matrices one at a time into position to be picked up by the screws, the said device comprising the vertical slide C formed with the slot C³, the stop pins C⁴, C⁵ arranged within the slot C³, the finger C¹ pivoted to the slide C and provided with the arm C² and projecting pin C⁸, the spring C⁷ connected to the pin C⁸, the operating lever D having its arm D² connected to the arm C², and a cam plate A⁴ arranged to engage the pin C⁸, all substantially as shown and described.

16. In a typographical distributing mechanism comprising a distributor bar and a set of matrix conveying screws, the combination of inclined guide means along which the matrices gravitate toward the screws, and an escapement device arranged to cooperate with the upper ends of the gravitating matrices and acting to control their escape one at a time into position to be picked up by the screws, said escapement device comprising a yieldable matrix arresting member and a matrix depressing member associated therewith, said depressing member in its upper position standing clear

of the descending matrices but acting during its downward stroke to depress the leading matrix and hold back the following matrices, and said arresting member in the upper position of the depressing member serving to arrest the leading matrix in engaging relation thereto and in the lower position of the depressing member being moved out of the way of the depressed matrix to permit its escape. 35

17. In a typographical distributing mechanism comprising a distributor bar and a set of matrix conveying screws, the combination of inclined guide means along which the matrices gravitate toward the screws, and an escapement device arranged to cooperate with the upper ends of the gravitating matrices and acting to control their escape one at a time into position to be picked up by the screws, said escapement device comprising a spring-actuated pivotally mounted arresting member arranged in the path of the descending matrices and a slidably mounted releasing member operative to depress the leading matrices as they are successively arrested by the arresting member in effecting their escape to the screws. 50 45

In testimony whereof, I have affixed my signature hereto.

JAMES G. McNAMARA.
